UNITED STATES PATENT OFFICE.

WILLIAM LUCIUS CHURCHILL, OF WHITE PLAINS, NEW YORK.

ELECTRIC RIVET-HEATER.

1,326,479.

Specification of Letters Patent. Patented Dec. 30, 1919.

Application filed October 7, 1918. Serial No. 257,171.

To all whom it may concern:

Be it known that I, WILLIAM LUCIUS CHURCHILL, a citizen of the United States, residing at White Plains, in the county of Westchester, State of New York, have invented new and useful Improvements in Electric Rivet-Heaters, of which the following is a specification.

This invention relates to devices and mechanisms for electric heating; and it is a primary object of this invention to provide a simple and effective mechanism for heating such articles as rivets and other things of like nature. And in the more specific aspects of my invention it is an object to provide a mechanism which is easily and quickly operated; and one which will quickly, efficiently and uniformly heat a rivet or the like to any suitable desired temperature, without underheating or overheating. It is also one of the objects of this invention to do away with the usual loss of rivets, loss of finished work, etc., by overheating and burning.

The invention will be best understood from the following detailed description of preferred forms of mechanism embodying the invention; reference being had for this purpose to the accompanying drawings in which I illustrate specific preferred forms of this device.

In these drawings Figure 1 is a front elevation of one form of my heating mechanism; Fig. 2 is a vertical section taken on line 2—2 of Fig. 1; Fig. 3 is a detail section taken as indicated by line 3—3 on Fig. 2; Fig. 4 is a section taken on line 4—4 of Fig. 2; Fig. 5 is a detail section taken on line 5—5 of Fig. 1; Fig. 6 is a front elevation of a modified form and arrangement of the device; and Fig. 7 is a vertical section thereof on line 7—7 of Fig. 6.

In the drawings I show pairs of carbon electrodes 10 and 11 situated one somewhat above the other and normally standing with their faces 10^a and 11^a in opposition to and close to each other, but not quite touching. These carbon electrodes are mounted so as to be relatively movable, one with relation to the other; and in order to effect this movement, and to make a practical and efficient mounting of the electrodes, I mount the lower electrodes 11 upon the stationary conductor bar 12 which is mounted upon and supported by a standard 13, a block 14 of insulating material being interposed to in-

sulate the connector bar 12 from the standard. The upper electrodes 10 are mounted upon an upper conductor bar 15 upon which a bracket 16 is mounted. Bracket 16 is carried, pivotally at 17, upon the end of an arm 18 pivoted at 19 to a bracket arm 20 which extends preferably from standard 13. A suitable spring means may be used to keep the bracket 16 and electrodes 10 in approximately correct relative position to bring the lower electrode faces 10^a down in parallel relation with the electrode faces 11^a; resilient means being used so as to allow the upper electrodes to more or less self-adjust themselves to cause the electrodes to fit snugly about the rivets, as will be herein-after described. For this purpose a flat spring or springs as shown at 25 may be used, secured to the bracket 16, with the free end adjustably connected, as indicated at 26, with the arm 18. From pivoted arm 18 a connecting rod 27 extends to foot lever 28 pivoted at 29. A rear extension 18 may carry a counterbalance weight 30; the office of this weight being to move the rear end 30 of the foot lever downwardly and thereby raise the pivoted arm 18 and raise the upper electrodes 10. Foot pressure upon pedal 31 will bring the upper electrodes down toward the lower electrodes and the foot lever 28 may then be swung in under the lug or catch 32 for the purpose of holding the foot lever down and holding the upper electrodes 10 in their lower position. The foot lever 28 may be loosely pivoted at 21 so that it has a certain amount of lateral motion to allow it to be swung under the lug 32. In order to always bring the electrodes down to proper position when the foot lever is under lug 32, a suitable spring means may be employed somewhere in the connection between the foot lever and the upper electrodes 10. Although this spring means may be placed at any point and arranged in any manner, it may easily be interposed in connecting rod 27 as shown at 27^a. The rod 27 may be passed through a lug or ear 35 on lever 28 and a compression spring 27^a arranged between a nut 27^b and the ear 35; while an adjustable nut at 36 may be employed to limit the downward movement of the electrodes 10, this nut being adjusted so that electrodes 10 will not quite make contact with the lower electrodes when the lever 28 is in the position shown in the drawings.

It will be noted that the electrodes are inclined somewhat rearwardly from the operator standing in front of the machine; so that a rivet placed at R between the electrodes in a position slopes somewhat downwardly toward the rear end. In the two opposing faces of each pair of electrodes there are grooves 40 cut or otherwise formed to receive a rivet R; and in the several sets of electrodes these grooves may be made of different sizes to take different sizes of rivets; so that, in this specific embodiment of my invention I preferably have facilities for handling different sizes of rivets without having to change electrodes. For instance, in the form of device shown in the drawings, I may have provision for handling four different sizes of rivets of the character shown at R in Fig. 2; and then in one of the pairs of electrodes I may have provision for handling different sizes of "counter-sunk" rivets; provision being made in these electrodes for holding the whole of the rivets, including the enlarged cone-shaped head, between the electrodes, so that in this case the head of the rivet as well as the shank is heated. In heating an ordinary headed rivet it is not particularly desirable to heat the head; so that in the ordinary case the head of the rivet is not placed between the electrodes. In Fig. 5 I indicate the shape of the grooves 40 for holding "counter-sunk" rivets, the forward ends of the grooves 40 being conically enlarged as indicated at 40^b. In each of the lower electrodes 11 notches 40^b may be formed on each side of the grooves 40 for insertion of the tongs to grasp and remove the heated rivets; these notches being made at the proper points to allow the tongs to be inserted and grasp the rivet at the proper place on its shank, so that the rivet may then be properly handled by the operator. Each of the electrodes may be heat insulated by a wall or layer of heat insulating material as indicated at 50.

Electrical connection is made to the two connector bars 12 and 15, by wires 51 and 52. In the electrical circuit, at some point, and not necessarily directly in the circuit which leads to the conductor bars 12 or 15, there may be a switch whose movable arm 54 is connected by rod 55 with the foot-lever 28; the arrangement being such that, as the foot-lever is raised, the electrodes 10 will raise off the rivets after the circuit is broken at the switch, thus obviating any arc which might otherwise take place between the carbon electrodes and the rivets.

The form of machine described may have any number of sets of carbon electrodes; or such a machine may be reduced to one set of electrodes; becoming, in such form, a simple machine of minimum complications and parts. Any such machine as herein described may have its electrodes fitted to re-

ceive different sizes of rivets or may have all of the electrodes fitted to receive only one size of rivets at a time, the electrodes being removable and replaceable by others. All such arrangements, as regards adaptability to heating different sizes and shapes of rivets, adaptability to heating more than one rivet at a time, etc., may be determined in the actual use of this machine. It will be noted that the carbon blocks are so arranged that they will take rivets of varying lengths without the necessity of changing the electrode blocks.

In Figs. 6 and 7 I show a modified arrangement of my machine, which, in some situations, may be the preferred form of device. The upper and lower carbon terminals 10 and 11 are made in such form as to be readily removable from the lower conductor bar 12 and the upper individual mounting block 60. The carbon blocks have a dovetail tongue fitting in corresponding grooves in the parts 12 and 60, so that the carbon blocks may be easily removed and replaced with others suitable for receiving different sizes and shapes of rivets. In the form of mechanism shown in Figs. 6 and 7 each one of the sets of electrodes is operative independently of the others by an individual foot pedal; and the electrodes may be either all designed to handle the same shape and size of rivet at one time, or may be designed to handle two or more different sizes of rivets. In fact, as a general feature of my invention, it will be readily seen that the number of sets of electrodes, and their operating mechanism, may be extended indefinitely; and the electrodes of proper conformation inserted in place to handle any number of the same sized or different sized rivets.

In this form of device, each upper carbon 10 is connected by a flexible connection 61, preferably a laminated sheet copper connection, to a common conductor bar 15 mounted upon the frame of the machine. Each upper carbon 10 is individually carried by a bracket 16 pivoted upon the end of an individual arm 18 pivoted on a pivot shaft 19 supported in supporting bracket or brackets 20. Each pivoted arm 18 is connected to its individual foot-lever 28 substantially in the manner hereinbefore explained. The operation of any one foot-lever causes the downward movement of the carbon 10 to clamp and hold the rivet in place. In using this form of my device it is intended that two or more of the electrodes may be at all times in operating relation holding a rivet, so that a current is passing through two or more of the electrodes at all times. For instance in a device having three elements as herein described, during a part of the time all three elements will be operating; and when a rivet is taken out of one

element, the circuit being broken when the carbons are opened, a new rivet is put in and these carbons closed before the circuit is broken at another element to remove a rivet therefrom. Thus the current is closed at some place at all times, and is preferably closed through at least two of the heating elements at all times; so that the arcing at the third element will be greatly reduced.

10 Furthermore, I may, in an installation of this character, provide an electrical supply which is only fully sufficient for, say, two elements; so that when the circuit is broken at a third element, there will be no arcing disastrous to the carbons.

15 I use a low voltage current with high amperage. The carbon blocks become heated throughout as well as the rivet; and I aim in actual operation to keep the blocks from 20 cooling between rivet heats so that the heat of the carbons is not lost.

25 In either form of my device, or in any modification or variation thereof, rivets are heated quickly and with the consumption of a small amount of current. They are, moreover, heated to a uniform temperature and are heated uniformly throughout. With a given size of rivet, a certain amount of current will heat the rivet to a certain 30 temperature in a known time period; or will only heat the rivet and electrode blocks to a certain maximum temperature in an indefinitely long time period.

35 Not only is my device more economical than other methods of heating rivets which are now in use, but it also saves those rivets which are at present lost on account of overheating and burning, and saves time which has been formerly lost in removing and 40 placing defective riveting due to improper heating. There are many other advantages of my invention which are not necessary to here mention.

Having described a preferred form of my 45 invention, I claim:

1. An electric heater for rivets or the like, embodying a pair of electrodes movable relatively one to the other and standing face to face when in operative relation, the 50 electrodes having semi-cylindrical cavities on their opposing faces adapted to receive the article to be heated; and means to move one of the electrodes away from the other to open up the space between them to release 55 the heated article.

2. An electric heater for rivets or the like, embodying a pair of electrodes movable relatively one to the other, the electrodes standing face to face when in operative relation 60 and having semi-cylindrical cavities on their opposing faces adapted to receive the article to be heated; a movable pivoted arm, one of the electrodes being pivotally mounted on the arm, so that by movement 65 of the arm the electrodes may be separated

and so that the electrodes have relative adjustability by movement of said pivoted electrode.

3. An electric heater for rivets or the like, embodying a pair of electrodes provided on 70 their opposing faces with semi-cylindrical rivet receiving recesses, a frame upon which one of the electrodes is mounted, a movable mounting for the other electrode, and manually operable means to move the second 75 mentioned electrode away from the first mentioned electrode, said means embodying means for normally holding the electrodes together.

4. In an electric heater for rivets or the 80 like, a pair of electrode blocks adapted to be held in position face to face and having on their opposing faces recesses adapted to fit around the rivet or the like.

5. In an electric heater for rivets or the 85 like, a pair of electrode blocks adapted to be held in position face to face and having on their opposing faces recesses adapted to fit around the rivet or the like, one of the blocks having tong recesses at opposite sides 90 of its rivet receiving recess.

6. In an electric heater for rivets or the like, a pair of electrode blocks one stationary and the other movable, a frame support for the stationary block on which said block is supported with its upper surface in a sloping position, and means to move the other electrode to and from a position in which one of its faces opposes the sloping 100 face of the stationary electrode, the opposing faces having semi-cylindrical rivet receiving recesses extending down the slope of said faces.

7. An electric heater for rivets or the like, embodying a frame, a conductor bar mounted thereon, a plurality of lower electrode blocks removably mounted on the bar, the bar being tilted down toward the back of the frame, a pivot shaft at the back of the frame, a plurality of arms mounted on 110 the pivot shaft and extending forwardly over the lower electrode blocks, upper electrode blocks carried at the ends of said arms, a conductor bar at the rear of the frame, flexible electrical connection between 115 said bar and the upper electrode blocks, and individual manually operable means for moving said arms and the upper electrode blocks.

8. An electric heater for rivets or the 120 like, embodying a frame, a conductor bar mounted thereon, a plurality of lower electrode blocks removably mounted on the bar, the bar being tilted so that the upper faces 125 of the blocks are tilted down toward the back of the frame, a pivot shaft at the back of the frame, a plurality of arms mounted on the pivot shaft and extending forwardly over the lower electrode blocks, upper electrode blocks carried at the ends of said 130

arms, said blocks being pivotally mounted on the arms and having a resilient attachment therewith to keep said blocks in alignment to present their lower faces in opposition to the upper sloping faces of the lower electrode blocks and allow adjustment movement of the upper blocks, a conductor bar at the rear of the frame, flexible elec-

trical connection between said bar and the upper electrode blocks, and individual 10 manually operatable means for moving said arms and the upper electrode blocks.

In witness that I claim the foregoing I have hereunto subscribed my name.

WILLIAM LUCIUS CHURCHILL.
